SPONGE TYPE MOP WITH TWO-PART
HINGED BACKING PLATEEric Åke Sjöblom, Koping, Sweden, assignor to
Erik Gustaf Backman, Koping, SwedenApplication January 23, 1950, Serial No. 140,108
In Sweden January 25, 1949

3 Claims. (Cl. 15—119)

1

This invention relates to a floor mop. It is an object of the invention to provide a floor mop, that can be used without touching the mop with the hands.

Another object is to provide a floor mop that is securely attached to the holder.

A further object of the invention is to provide a floor mop that will permit easy compression of the mop to remove the cleaning fluid.

A still further object is to provide a floor mop that easily can be used under low standing furnitures and the like.

These and other objects and advantages are attained by the floor mop of the invention which in its preferred embodiment includes a compressible sponge removably attached to two pivotable flaps operated by means of a cord and a lever on a swingable handle.

The invention will be more particularly described with reference to the illustrative embodiments of the invention shown in the accompanying drawings in which:

Fig. 1 is an end elevation of the floor mop in operating position on a handle;

Fig. 2 is an end elevation of the floor mop with the flaps pivoted to compress the sponge;

Fig. 3 is a plan view of the floor mop in operating position;

Fig. 4 is a plan view of another embodiment of the pivotable provision of the flaps;

Fig. 5 is a fragmentary view of the same;

Fig. 6 is a cross-section of the connection of the holder in Fig. 1 with the handle, and

Fig. 7 is a fragmentary view of the pivot of Fig. 6 shown from the side.

In the drawings 1 and 2 indicate two elongated compression flaps which are pivotably connected by a shaft 14, the opposite long sides of which are provided with projecting plate strips bent around the shaft 14. The flaps are bent twice transversely, the first bend sloping slightly downwards, whereas the free long sides of the flaps are bent approximately 90 degrees. A rubber sponge 4 is held against the under faces of the flaps by a rubber strap or spring 5 arranged longitudinally thereof and provided with hooks introduced into each end of the pivot. The compression of the rubber sponge according to Fig. 2 is effected by compression levers 6 and 7 firmly attached to the upper face of each flap approximately at the middle thereof, the free ends of said levers extending along or overlap the opposite flap. The flaps are held in opened position by transversal springs 13 attached at the long sides of each flap, the free ends of said levers

2

forming an abutment for the opposite flap. The shaft 14 is hinged to spaced plates 15, 16 firmly connected to a handle 17 by bolts, between which plates guide pulleys 9, 10 and 11 are rotatably arranged and provided with concave grooves. Over said guide pulleys a steelwire 8 is run, the ends of which are attached each to its own free end of the compression levers 6 and 7. The steelwire 8 passes over a guide member or pulley 12 on a single-armed actuating lever 12 pivotedly connected by a pin 12' to the handle 17 (Fig. 1).

Referring to Fig. 2 of the drawings the flaps are shown in folded position, the cleaning fluid squeezed from the sponge being allowed to escape through the apertures shown in Fig. 3 arranged longitudinally in the flaps adjacent the long edge thereof bent 90 degrees.

The pivotable connection of the flaps may also be established by the embodiment shown in Figs. 4 and 5, the flaps of which are provided with two elongated apertures at the opposite long edges, said apertures being adapted to receive rings 3 connecting the two flaps. Said rings on their upper faces have projecting pins 18 to be connected with the plates 15 and 16 by riveting or welding.

In using the floor mop according to the invention the sponge is attached to the flaps 1, 2 by means of the spring 5. Preferably the sponge is slightly longer than the flaps, so that the projecting parts serves as a protection at occasional collisions with furnitures and the like. Due to the handle 17 it is possible to work with the handle in any desired position from a vertical to a nearly horizontal position without changing the relative position of the flaps. In order to squeeze the cleaning fluid from the sponge the operating lever 12 is moved upwards and back, the wire 8 running over the guide pulleys 9, 10, 11 actuating the flaps 1 and 2 to fold them together and at the same time compressing the sponge 4. In moving the lever back to the initial point the flaps are also opened to their initial positions by means of the springs 13.

What I claim is:

1. A floor mop comprising a pair of hinged flaps movable to either an opened or closed position, a compressible sponge connected to the underside of said flaps, spring means connected to said flaps and extending transversely thereof for normally maintaining the flaps and sponge in their opened mopping position, each of said flaps having a compression lever extending upwardly and outwardly therefrom to overlap and abut the opposite flap when the flaps are in

their opened position, an operating handle pivotally connected to said flaps, and means operatively connecting the levers to said operating handle for moving the levers toward each other and the flaps and sponge to their closed position to compress the sponge.

2. A floor mop comprising a pair of hinged flaps movable to either an opened or closed position, a compressible sponge connected to the underside of said flaps, spring means connected to said flaps and extending transversely thereof for normally maintaining the flaps and sponge in their opened mopping position, each of said flaps having a compression lever extending upwardly and outwardly therefrom to overlap and abut the opposite flap when the flaps are in their opened position, an operating handle pivotally connected to said flaps, flexible means connected to the compression levers, and means carried by said handle and operatively connected to said flexible means for moving the levers toward each other and the flaps and sponge to their closed position to compress the sponge.

3. A floor mop comprising a pair of flaps, a hinge pin pivotally connecting the inner opposed ends of the flaps so that they may be moved to either an opened or closed position, a compressible sponge connected to the underside of said flaps, spring means connected to said flaps and extending transversely thereof for normally maintaining the flaps and sponge in their opened mopping position, each of said flaps having a

compression lever extending upwardly and outwardly therefrom so as to overlap and abut the opposite flap when the flaps are in their opened position, a pair of spaced plates pivotally connected to said hinge pin, an operating handle connected to said plates above said hinge pin, spaced pulleys between said plates and journaled thereto, an actuating member pivotally connected to said handle and having a guide member thereon, and flexible means connected at its ends to said compression levers and passing over said pulleys and guide member so that upon operation of the actuating member the levers move toward each other and the flaps and sponge to their closed position to compress the sponge.

ERIC ÅKE SJÖBLOM.
